UNITED STATES PATENT OFFICE.

AUGUST HIRLINGER, OF CINCINNATI, OHIO.

FOLDING CRATE.

1,306,338.

Specification of Letters Patent. Patented June 10, 1919.

Application filed January 24, 1916. Serial No. 73,932.

To all whom it may concern:

Be it known that I, AUGUST HIRLINGER, a citizen of the United States, residing at Hyde Park, Cincinnati, in the county of 5 Hamilton and State of Ohio, have invented certain new and useful Improvements in Folding Crates, of which the following is a specification.

This invention relates to improvements in 10 folding crates and has for its object to provide a crate or box having its walls so arranged that they may be folded upon one another into a very compact space.

Another object of the invention is to provide 15 a crate having its side walls and top wall members hingedly connected together.

And still another object of the invention is to provide a slatted crate so arranged that the slats of one part of the crate may inter- 20 mesh with the slats of another part thereof whereby a plurality of walls or sides will only occupy a little more space than that equal to the thickness of one wall or side of the crate.

25 With the above and other objects in view which will hereinafter more fully appear, I have invented the device illustrated in the accompanying drawings in which:—

Figure 1, is a top plan view of my device 30 shown knocked down,

Fig. 2, is a sectional view taken on line 2—2 Fig. 1,

Fig. 3, is a perspective view of the invention shown set up,

35 Fig. 4, is an enlarged detail sectional view taken on line 4—4 Fig. 3, and

Fig. 5, is a plan view of the device with all of its parts extended and shown lying in a common plane.

40 Like reference characters indicate like parts throughout the specification and in the several views in the drawings in which 1 indicates a bottom wall which is of a size equal to the combined area of the two end 45 walls 2 and 3 which are hinged thereto. The bottom 1 is also of a size approximately that of each of the two members 4 and 5 each of which consists of a side wall and a top wall member, said side walls being hingedly connected to said bottom.

When the crate is set up the walls 2, 3, 6, and 7 are held connected and in a vertical position by means of catches or hooks 8 which may be of any kind most suitable for 55 the purpose. The walls 4 and 6 are con-

nected by hinges 9 and 10 and the walls 5 and 7 are connected by hinges 11 and 12.

The member 4 is provided with braces 13 and 13' and 14 and 14' which connect the slats 15 and 16 and are fastened to their inner surfaces. The member 5 is provided with braces 17 and 17' and 18 and 18', which are fixed to the slats 19 and 20 on the outer surfaces thereof in order that the slats 19 and 20 may lie within the spaces between the slats 15 and 16 when the crate is folded. Thus when the members 4 and 5 are folded upon one another the slats 15, 16, 19 and 20 will all lie in a common plane. The side 6 is connected to the bottom 1 by hinges 21 and 22 and the side 7 is connected to the bottom by hinges 23 and 24, said hinges 21 to 24 being elevated to enable the parts 4 and 5 to fold over the parts 2 and 3.

When the crate is knocked down the members 2 and 3 are first folded upon the bottom 1, then the member 4 is folded over the members 2 and 3 and finally the member 5 is folded upon the member 4 the slats of the members 4 and 5 intermeshing, thus making a very flat compact package for shipping empty and for storing. Bolts 25 are hingedly connected to the sides 2 and 3 and are adapted to project through slots 26 in the slats 15' and 16' and held fixed to said slats 15' and 16' by means of wing nuts 27 and 28.

I claim—

1. A crate having a bottom, side walls hinged to the sides thereof and a top section hinged to each side wall, end walls hinged to 90 said bottom and adapted to fold thereupon, one of said side walls and its top section adapted to fold upon said end walls and the other side wall and its top section adapted to fold against said first side wall and its top 95 section, all of said walls and top sections being formed of slats, the slats of said side walls and top sections being arranged to intermesh when folded to form a tight closure for the crate when folded, braces on the outer surface of one of said side walls and its top section and braces on the inner surface of the other side wall and its top section whereby the intermeshing of the slats of said members may be free to intermesh. 100

2. A crate having a bottom, side walls hinged to the sides thereof and a top section hinged to each side wall, end walls hinged to 105 said bottom and adapted to fold thereupon, one of said side walls and its top section 110

adapted to fold upon said end walls and the other side wall and its top section, all of said walls and top sections being formed of slats, the slats of said side walls and top sections being arranged to intermesh when folded to form a tight closure for the crate when folded, braces on the outer surface of one of said side walls and its top section and braces on the inner surface of the other side wall and its top section whereby the intermeshing of the slats of said members may be free to intermesh, hinged screw bolts mounted upon certain of said walls and thumb nuts whereby said crate may be fixed in set up position.

3. In a folding slatted crate, hinged sides, a top section hinged to each of said sides, the slats of one side and top section adapted to intermesh with the slats of the other side and top section.

4. In a folding slatted crate, hinged sides, a top section hinged to each of said sides, the slats of one side and top section adapted to intermesh with the slats of the other side and top section, a bottom to which said sides

are hinged, and ends hinged to said bottom and adapted to fold under said sides and top sections.

5. In a folding slatted crate, hinged sides, a top section hinged to each of said sides, the slats of one side and top section adapted to intermesh with the slats of the other side and top section, cleats on the inside of one of said side and top sections for holding the slats thereof together.

6. In a folding slatted crate, hinged sides, a top section hinged to each of said sides, the slats of one side and top section adapted to intermesh with the slats of the other side and top section, cleats on the inside of one of said side and top sections, and cleats on the outside of the other of said sides and top sections whereby the slats of said sides and top sections are held together.

In testimony whereof I affix my signature in the presence of two witnesses.

AUGUST HIRLINGER.
